UNITED STATES PATENT OFFICE.

PETER G. MACGREGOR, OF PEQUANNOCK, NEW JERSEY, ASSIGNOR TO PYRENE MANUFACTURING COMPANY, OF NEWARK, NEW JERSEY, A CORPORATION OF DELAWARE.

OUTLET GUARD.

Application filed July 24, 1925. Serial No. 45,782.

This invention relates to outlet guards for liquid receptacles particularly adapted to guard the outlets of fire extinguishers of the types containing a liquid held within the receptacle and another liquid adapted to react with the first mentioned liquid to produce a gas, the last mentioned liquid held within a container carried in the receptacle or otherwise normally separated from the first mentioned liquid, the fire extinguishers being adapted to be put into operation by inverting them or otherwise causing the two liquids to come in contact with each other, whereby a gas is generated which creates a pressure acting to discharge the liquid contents of the receptacle through the outlet opening, the latter usually arranged at the top of the receptacle and above the normal level of the liquid in the receptacle. Such fire extinguishers may be of the pressure type or the foam type.

With fire extinguishers of the pressure or foam type it has been found difficult to prevent the escape of liquid from the receptacle when subjected to undue shaking or agitation, such, for example, as that resulting from the movements of a railway car or other vehicle upon which the extinguisher is carried.

An object of the invention is to provide an outlet guard which is adapted to be connected to the inner wall of the fire extinguisher adjacent the outlet thereof and is so constructed as to prevent escape of the liquid due to slopping action thereof.

Another object of the invention is to provide a guard of the character mentioned which, while it functions effectively to prevent the escape of liquid by slopping action, is readily accessible for cleaning without uncovering its strainer or moving any part of it from normal position, and which, while it will effectively prevent undue escape of liquid when the extinguisher is not in use, will nevertheless permit an unrestricted flow of the liquid through the outlet when the extinguisher is put into operation.

Other objects and advantages of the invention will become apparent from the following description when taken in connection with the accompanying drawings in which—

Figure 1 is an elevation, partly in section, of the upper portion of a fire extinguisher

having my improved outlet guard applied thereto.

Figure 2 is a vertical sectional view through the outlet guard and the fire extinguisher outlet.

Figure 3 is a face view of the outlet guard.

Figure 4 is a face view of a baffle plate.

Figure 5 is an edge elevation of the baffle plate as viewed from above in Figure 4.

The drawings show a fire extinguisher of the type adapted to be normally held or carried in an upright position and to be inverted to effect a mixing of the liquids when it is desired to place the extinguisher in operation. The receptacle 5 of the extinguisher herein shown is provided with the usual removable cover 6 and with the outlet 7, the latter carrying a discharge hose 8 and communicating with the receptacle 5 at the upper end thereof above the normal liquid level.

The outlet 7 is provided with a flange, as shown in Figures 1 and 2, and is adapted to be brazed or otherwise suitably connected to the wall of the extinguisher. Over the inner end of the outlet 7 is positioned the outlet guard embodying my invention and shown as comprising a baffle plate 9, which is secured, as by soldering, to the inner wall of the extinguisher, and is so formed as to provide an overhanging deflecting wall 10

which carries an annular seat 11 and is connected to a concavo-convex centrally located shield portion 12 by means of radial arms 13, between which are formed arcuate-shaped openings 14. This centrally located shield portion 12 is located at such a distance from the opening of the outlet, and the openings between the radial arms 13 are of such width, as to provide an ample runway for liquid to the outlet opening when the receptacle is inverted. It will be noted that the shield portion 12 is somewhat larger than the opening of the outlet 7 and that this is arranged concentrically with the entrance to the outlet 7. By reason of the fact that the shield portion is positioned directly in

front of the opening of the outlet and overlaps it in all directions, it affords an effective obstruction to any liquid which may be unduly directed toward the outlet from the front or convex side of the baffle plate. The deflecting wall 10 is, as shown most clearly

in Figure 2, so extended that a plane coincident with the front edge thereof is further from the outlet opening than the plane of the outer edge of the shield portion 12, and thus 5 the deflecting wall overlaps the entrance to the outlet in planes at right angles to the axis of the opening. It is obvious that the deflecting wall 10 will effectively obstruct and throw back away from the outlet such 10 liquid as may be unduly directed toward the entrance to the outlet along the wall of the receptacle within the range of contact with the deflecting wall, and that any splashing liquid which approached clear of the deflecting wall and which escaped the backflow 15 caused by the deflecting effect of this overhanging wall, would be obstructed by the shield portion 12.

In order to further obstruct undue passage of liquid from the extinguisher into the outlet 7, a perforated concavo-convex guard plate 15 is provided. This guard plate is adapted to be suitably connected, as by means of solder, to the baffle plate 9, this guard 20 plate having a flange 16 adapted to rest upon the annular seat 11 of the baffle plate 9. The perforations in this guard plate 15 provide ample passageways for the liquid during 25 normal operation of the extinguisher, but the portions of the guard plate between the perforations obstruct the passage of liquid by splashing and the guard plate, as a whole, acts as a strainer. By reason of the coaction 30 of this guard plate 15 with the other features of my invention it does not have to be covered or externally shielded and is therefore readily accessible for cleaning.

In order that the outlet guard, in its entirety, may be fitted snugly to the wall of the extinguisher, both the baffle 9, and the guard plate 15 are cut away at the top, as shown 40 most clearly in Figures 3 and 4, to accommodate them to the neck 17 or other obstruction at the upper end of the extinguisher.

45 What I claim is:—

1. An outlet guard for liquid receptacles, comprising a baffle plate attached to the receptacle and positioned in front of the outlet, and a perforated guard plate positioned 50 in front of and attached to the baffle plate and spaced therefrom.

2. An outlet guard for liquid receptacles, comprising a baffle plate permanently attached to the receptacle and positioned in front of the outlet, and a perforated guard plate positioned in front of and permanently attached to the baffle plate and spaced 55 therefrom.

60 3. An outlet guard for liquid receptacles, comprising a baffle plate attached to the receptacle and positioned in front of the out-

let, a deflecting wall on the baffle plate extending inward from the wall of the receptacle, and a perforated guard plate positioned in front of and attached to the 65 baffle plate and spaced therefrom.

4. An outlet guard for liquid receptacles, comprising a baffle plate attached to the interior of the receptacle and positioned in front of and spaced away from the outlet, 70 a deflecting wall on said baffle plate extending inward from the wall of the receptacle, and a perforated guard plate positioned in front of and attached to the baffle plate and spaced therefrom. 75

5. An outlet guard for liquid receptacles, comprising a baffle plate attached to the interior of the receptacle and positioned in front of and spaced away from the outlet, 80 a deflecting wall on the baffle plate extending inward from the wall of the receptacle, and a perforated guard plate positioned in front of and attached to the baffle plate and positioned within the deflecting wall. 85

6. An outlet guard for liquid receptacles, comprising means for preventing the contents of the receptacle from entering the outlet when subjected to a slopping action, said means comprising a baffle plate attached to the inner wall of the receptacle and positioned in front of the outlet, a deflecting wall on the baffle plate extending inward from the wall of the receptacle, and a perforated guard plate attached to and positioned in front of the baffle plate and spaced 90 therefrom, the deflecting wall serving to divert liquid from the perforated guard plate 95 when the liquid is subjected to a slopping action.

7. An outlet guard for liquid receptacles 100 comprising a baffle plate having a concavo-convex shield portion positioned in front of the outlet and a concavo-convex perforated guard plate positioned in front of the shield portion and spaced therefrom and a deflecting wall adjacent the guard plate and outlet, the baffle plate and the guard plate being anchored with respect to each other and with respect to the outlet. 105

8. An outlet guard for liquid receptacles, comprising a baffle plate having a shield portion positioned in front of the outlet and provided with a deflecting wall, and a perforated guard plate positioned in front of the shield portion and spaced therefrom, 110 the guard plate being seated upon the baffle plate intermediate the shield portion and the deflecting wall. 115

In testimony whereof, I have affixed my signature to this specification.

PETER G. MACGREGOR.
